H. E. YARROW.

AIR VALVE FOR FURNACES USING LIQUID FUEL.

APPLICATION FILED OCT. 30, 1917.

1,312,378.

Patented Aug. 5, 1919.

UNITED STATES PATENT OFFICE.

HAROLD E. YARROW, OF GLASGOW, SCOTLAND.

AIR-VALVE FOR FURNACES USING LIQUID FUEL.

1,312,378.

Specification of Letters Patent.

Patented Aug. 5, 1919.

Application filed October 30, 1917. Serial No. 199,313.

To all whom it may concern:

Be it known that I, HAROLD EDGAR YARROW, a subject of the King of Great Britain, residing in Glasgow, Scotland, have invented 5 a certain new and useful Air-Valve for Furnaces Using Liquid Fuel, of which the following is a specification.

The invention relates to means for controlling the flow of air to a furnace burning liquid fuel and comprises a valve which is adapted to control the supply of air and at the same time to act as a safety device to prevent, in the case of a "blow back" or rise of pressure in the furnace, the escape of air, 15 gas or steam into the stokehold. The construction of the valve and of the valve seating also allows a whirling motion to be imparted to the air entering the furnace.

In the accompanying drawing which 20 shows an example of a construction according to the invention, Figure 1 is a front elevation and Figs. 2 and 3 sections on the lines 2—2 and 3—3 respectively of Fig. 1.

The seating, or fixed part, A of the air 25 valve is in the form of a frustum of a hollow cone; in the sides of the cone are a number of ports or passages B, which may be provided with directing vanes C in order to impart a whirling motion to the air which enters the furnace both through and around 30 the mixing chamber J.

These vanes are supported by bars D between the ports B. The vanes may be omitted entirely, or at certain positions, leaving 35 clear passages as shown at E.

The valve F is of similar form to A and is shown in the fully open position by dot and dash lines in Fig. 2 and by full lines in the closed position. The construction is such 40 that in the closed position of the valve, ports G of the valve are opposite to the bars D in the seating and bars H between the ports of the valve are opposite to the ports B of the seating, so that in this position the air supply to the furnaces is entirely cut off, and 45 the air supply can be controlled as required by moving the valve toward or away from the seating. The ports G may be provided with directing vanes I, in order to impart a whirling motion to the air, or they may be clear passages. The plane end of the valve F is, preferably, lined with asbestos as 50 shown at M.

The valve, F, is supported, in the example 55 shown, on rollers K, but any suitable means may be adopted to move the valve in the

direction of the common axis of the valve and seating.

In the event of a "blow back" or rise in pressure in the furnace, the blast of air, gas 60 or steam striking the plane end L of the valve F causes it to move rapidly into contact with the seating A, thereby closing all ports and preventing any danger to the men in the stokehold. 65

Having thus fully described the nature of my said invention and the best means I know of carrying the same into practical effect, I claim:

1. Means for controlling the supply of air 70 to a furnace burning liquid fuel comprising in combination a fixed seating in the form of a frustum of a hollow cone, a valve also in the form of a frustum of a hollow cone coaxial with the said seating and having a 75 plane end subject to the pressure of the gases within the furnace to automatically move the valve in the direction of the common axis of the cones to close the valve upon a rise of pressure in the furnace. 80

2. Means for controlling the supply of air to a furnace burning liquid fuel comprising in combination a fixed seating in the form of a frustum of a hollow cone, a valve also in the form of a frustum of a hollow cone 85 coaxial with the said seating and having a plane end subject to the pressure of the gases within the furnace to automatically move the valve in the direction of the common axis of the cones to close the valve upon a 90 rise of pressure in the furnace, and an anti-friction support for the valves. 95

3. Means for controlling the supply of air to a furnace burning liquid fuel comprising in combination a fixed seating in the 95 form of a frustum of a hollow cone having ports and bars in its inclined sides, a valve also in the form of a frustum of a hollow cone, a valve also in the form of a frustum of a cone coaxial with the said seating and 100 having ports and bars in its inclined sides adapted to register with the bars in the seating in the closed position of the valve, said valve having a plane end subject to the pressure of gases within the furnace and caused 105 by a rise of pressure in the furnace to cause the valve to automatically move into closed position.

4. Means for controlling the supply of air to a furnace burning liquid fuel comprising in combination a fixed seating in the 110 form of a frustum of a hollow cone, direct-

ing vanes on the said seating, a valve also in the form of a frustum of a hollow cone coaxial with the said seating and means carried by the valve and subject to the pressure of gases within the furnace to cause the valve to move automatically in the direction of the common axis of the cones and close the valve if a rise of pressure occurs in the said furnace.

- 10 5. Means for controlling the supply of air to a furnace burning liquid fuel comprising in combination a fixed seating in the form of a frustum of a hollow cone, a valve also in the form of a frustum of a hollow cone

coaxial with the said seating, directing vanes 15 on the said valve, and means carried by the valve and subject to the pressure of gases within the furnace to cause the valve to move automatically in the direction of the common axis of the cones and close the valve if a 20 rise of pressure occurs in the said furnace.

In testimony whereof I have signed my name to this specification in the presence of two subscribing witnesses.

HAROLD E. YARROW.

Witnesses:

JAMES RITCHIE,
SILVESTER LYTTON.
